[57] CLAIM

The ornamental design for a slant board or similar article, substantially as shown and described.

DESCRIPTION

FIG. 1 is a perspective view of a slant board or similar article showing my new design;

FIG. 2 is an end elevational view thereof;

FIG. 3 is a side elevational view thereof, the side opposite being substantially a mirror image;

FIG. 4 is an end elevational view thereof showing the end opposite that shown in FIG. 3.

FIG. 5 is a bottom plan view thereof, and

FIG. 6 is another side elevational view thereof showing the design in a collapsed condition.

FIG. 1

FIG. 2

FIG. 3

FIG. 4
